UNITED STATES PATENT OFFICE.

OSCAR URIAH CHENOWETH AND JESSE W. CHENOWETH, OF OTTERBEIN, INDIANA.

BOILER.

No. 860,728.

Specification of Letters Patent.

Patented July 23, 1907.

Application filed August 29, 1906. Serial No. 332,444.

To all whom it may concern:

Be it known that we, OSCAR URIAH CHENOWETH and JESSE W. CHENOWETH, citizens of the United States, residing at Otterbein, in the county of Benton and 5 State of Indiana, have invented certain new and useful Improvements in Flash-Boilers, of which the following is a specification.

Our invention relates to flash boilers of the type usually used in automobiles and has for its object the 10 provision of a boiler of this character constructed in such manner that all of the parts thereof may be efficiently heated and also constructed in such manner that the connecting pipes between the unit coils, which combine to form the boiler, serve as water traps to prevent a circulation being set up in the boiler.

Further objects and advantages of the invention will be set forth in the detailed description which now follows:

In the accompanying drawing: Figure 1 is a side 20 elevation of a flash boiler constructed in accordance with our invention, with the coils slightly separated to preserve the clearness of the drawing, and Fig. 2 is a plan view of the boiler shown in Fig. 1.

Like numerals designate corresponding parts in both 25 of the figures of the drawing.

The boiler forming the subject matter of the present invention consists of a plurality of units, each of said units consisting of two coils, the lower of said coils being in the form of a spiral and the upper of said coils 30 being formed of a series of radial loops. These units are connected by pipes which extend vertically at the sides of the boiler, and pipes which extend horizontally across the top of the boiler, by virtue of which latter construction water traps are formed between each of 35 the units and circulation directly through the boiler is thereby prevented.

It is to be understood that all the coils will lie in contact with each other, the radial loops serving as spacing members to space the spiral coils from each 40 other. In order to preserve the clearness of the drawing and to describe with exactitude the method of operation of the boiler, the coils have been shown slightly separated in Fig. 1 instead of in contact with each other.

45 Referring to the drawing, the numeral 5 designates the spiral coil of the first unit, while the numeral 6 designates the radial loop coil of said unit. The numeral 7 designates the spiral coil of the second unit, while the numeral 8 designates the radial loop coil of 50 said second unit. The numeral 9 designates the spiral coil of the third unit, while the numeral 10 designates the radial loop coil of said third unit. The numeral 11 designates the spiral coil of the fourth unit, while the 55 numeral 12 designates the radial loop coil of said fourth unit. A horizontal pipe 13 which extends across the top of the boiler and a vertical pipe 14 connect the coil

6 of the first unit with the coil 7 of the second unit. A vertical pipe 15, a horizontal pipe 16 and a vertical pipe 17 connect the coil 8 of the second unit with the coil 9 of the third unit. A vertical pipe 18, a horizontal pipe 19 and a vertical pipe 20 connect the coil 10 of the third unit with the coil 11 of the fourth unit. A vertical pipe 21, a horizontal pipe 22 and a pipe 23 connect the coil 12 of the fourth unit to the engine, not shown.

65 This boiler is formed of tubing which may be located over any desired form of burner. The coil 5 is connected at 25 to a source of water supply. The water flows through the spiral coil 5 and rises at 26 to the coil 6. It will be understood that in its passage through 70 the boiler the water will be converted into steam, the water or steam passing from coil 6 through pipes 13 and 14 to coil 7. It rises from coil 7 at 27 to coil 8, passing thence through pipes 15, 16, and 17 to coil 9. It rises at 28 from coil 9 to coil 10, passing thence through 75 pipes 18, 19, and 20 to coil 11. It rises from coil 11 at 29 to coil 12, passing from coil 12 through the pipes 21, 22 and 23 to the engine, having by this time been converted into superheated steam.

80 It is apparent that any number of units may be employed to form the boiler. These units are counterparts of each other and it is only necessary to supply vertical and horizontal connecting tubes to build up a boiler of any desired size. It is also apparent that by virtue of this construction a burned out unit may 85 be removed and another substituted therefor without disturbing any of the other units.

It is apparent from the foregoing description that the present boiler comprises a plurality of units, each 90 of said units consisting of two coils, the water first entering the lowermost coil of the upper unit, rising thence to the upper coil of the upper unit, passing thence to the lower coil of the second unit, then rising to the upper coil of the second unit, then passing to the lower coil of the third unit, then rising to the upper coil of the third unit, and so on through whatever number of units the boiler may consist of.

95 By referring to Fig. 2 of the drawing, it will be seen that the vertical connecting pipes which connect the various units are all located upon opposite sides of the boiler instead of being spaced around said boiler. It is by virtue of this construction that we are enabled to remove one of the coils without disconnecting the rest of the coils, for by locating these vertical pipes at the opposite sides of the boiler an open space is left at 100 the front or rear of the boiler through which any single unit may be withdrawn if said unit should be burned out.

105 A boiler constructed as herein set forth is very light and presents considerable of its area to the action of the flames. It consequently steams rapidly.

110 While the elements herein shown and described are

well adapted to serve the purposes for which they are intended, it is to be understood that our invention is not limited to the precise construction set forth, but includes within its purview such changes as may be 5 made within the scope of the appended claims.

What we claim, is:

1. A boiler of the character described, comprising a plurality of units, each of said units comprising two coils one of said coils being spirally formed and the other of said 10 coils being formed of a series of radial loops, and pipes for connecting the upper coil of each unit with the lower coil of the next lower unit, said pipes extending across the top of the boiler and forming water traps.
2. A boiler of the character described, comprising a plurality of units each of said units comprising two coils and tubes for connecting the upper coil of each unit with the lower coil of the next lower unit, said tubes comprising 15 vertical portions and horizontal portions, said horizontal portions extending across the top of the boiler and said 20 vertical portions of all of the tubes being located at the

sides of the boiler, leaving an unobstructed space at the front of the boiler through which any of the units may be withdrawn.

3. A boiler of the character described comprising a plurality of units, each of said units comprising two coils 25 one of said coils being spirally formed and the other of said coils being formed of a series of radial loops, and pipes for connecting the upper coil of each unit with the lower coil of the next lower unit, said pipes comprising 30 vertical portions and horizontal portions, the horizontal portions of said pipes extending across the top of the boiler and the vertical portions of said pipes being located upon opposite sides of the boiler, thereby leaving an unobstructed space through which any of the units may be withdrawn, said connecting pipes forming water traps. 35

In testimony whereof we affix our signatures in presence of two witnesses.

OSCAR URIAH CHENOWETH.
JESSE W. CHENOWETH.
